CENTRALIZED TRAFFIC CONTROLLING
SYSTEM FOR RAILROADSThomas J. Judge, Rochester, N. Y., assignor to
General Railway Signal Company, Rochester,
N. Y.

Application February 26, 1942, Serial No. 432,428

11 Claims. (Cl. 246—3)

The present invention relates to centralized traffic controlling systems and more particularly to a centralized traffic controlling system of the unit line wire type in which a control and an indication may be transmitted over the same line circuit contemporaneously.

It is well understood by those skilled in the art of railway signalling that the cost of line wires is an important factor in any centralized traffic controlling system and that for this reason the number of line wires should be kept at a minimum. It is common practice to use the same line wire for transmitting controls in one direction and transmitting indications in the other direction at different times, in accordance with the present invention, however, it is proposed to transmit such controls and indications over the same line circuit by allotting the line circuit alternately for transmitting controls and indications at such a rapid rate that slow acting relays will manifest continuous reception of a control or an indication in spite of its intermittent interruption. In other words, it is proposed to transmit such a control and indication contemporaneously over a single circuit.

In view of the above and other considerations it is proposed, in accordance with the present invention, to employ double-throw contacts at a central office and at a field station each of which alternately connect that end of the line circuit to a control source of current or an indication relay at the office or to an indication source of current or a control relay at the field station, these double-throw contacts being operated at different rates such that control circuits and indication circuits are established intermittently at substantially the beat frequency of such rates. In the specific form of the invention illustrated two line circuits of the construction described are employed.

Other objects, purposes and characteristic features of the present invention will in part be obvious from the drawings and will in part be understood from the following specification when considered in the light of the accompanying drawings, of which:

Fig. 1A and Fig. 1B conventionally illustrate a system of centralized traffic control and indication embodying the present invention; and

Fig. 2 illustrates graphically the operation of the two double-throw contacts as well as graphically showing the circuits intermittently established thereby.

Structure.—Referring to Fig. 1B it will be seen that a portion of a passing siding PS has been

5 illustrated including a track switch SW operated by a switch machine SM, the position and locked condition of which track switch and switch machine is manifested by a switch indication relay WP. Switch indication correspondence relays NWP and RWP which when energized manifest that the switch control relay WZ and switch indication relay WP assume corresponding normal and reverse positions, respectively. This track switch SW is provided with the usual detector track circuit isolated from adjacent track circuits by insulating joints 9, and including a track battery B and a track relay T. The signals 1 and 1A govern the movement of traffic from east to west, that is, from right to left into the main track and side track, respectively, of the passing siding PS, whereas the signals 2 and 2A govern the movement of east-bound traffic off of the main track and the side track of the passing siding, respectively. These signals 1, 1A, 2 and 2A 10 may be of any well known construction, such as semaphore signals, multiple unit light signals, or searchlight type signals, and for convenience only semaphore signals have been conventionally 15 illustrated. A signal-at-stop relay M has been illustrated, this relay M being controlled by contacts 16, 17, 18 and 19 of the signals 1A, 1, 2A and 2, respectively, and being energized when all of these signals assume the stop position or 20 condition as is evident from these closed contacts with the signals at stop. These signals are controlled in accordance with traffic conditions in advance and by the signal control relay GZ, whereas the switch machine SM is controlled by a 25 switch control relay WZ.

Referring now to the central office shown in Fig. 1A a miniature track layout including a miniature representation of the passing siding PS has been illustrated by the miniature passing siding ps. This miniature passing siding ps has 30 associated therewith a track occupancy indicating lamp TE which when illuminated manifests that the detector track circuit at the field station shown in Fig. 1B is occupied. Some other well known form of indicator may of course be used in place of each of the several indicating lamps shown. The miniature track layout is also provided with indicating lamps or other suitable indicators OCE, GLE and GE. Of these indicators 35 the indicator OCE when lighted manifests that the track switch SW and the track switch control lever SML assume out of correspondence positions. The electric lock indicator GLE when rendered active manifests that the signal lever SGL is assuming a clear position and/or an indicator GE which

cation of occupancy of the detector track circuit and/or the clear indicating condition of a signal is to be expected by the indicator GE or TE becoming active. The office apparatus is also provided with an out-of-correspondence relay OCR and with indication relays WKP and TGKP, the control of which relays and the functions which they perform will be described hereinafter.

The line circuit over which switch controls and switch indications are transmitted includes a line wire WZ—WK and a common return wire C, whereas the line circuit over which signal controls, signal indications, and track occupancy indications are transmitted includes a line wire GZ—GK—TK and the same common return wire C. The central office end of these line wires WZ—WK and GZ—GK—TK are connected to double-throw contacts 10 and 12, whereas the opposite ends of these line wires are connected to double-throw contacts 11 and 13. The double-throw contacts 10 and 12 are at times intermittently operated to their opposite positions alternately by a coder 75CT operating at a rate to repeatedly pick up these contacts 10 and 12 seventy-five times per minute, whereas the double-throw contacts 11 and 13 are similarly intermittently operated by a coder 120CT which operates these contacts 11 and 13 alternately to their two extreme positions one hundred twenty times per minute. These coders 75CT and 120CT may be of any well known construction and preferably are provided with interrupter contacts 14 and 15, respectively, for causing intermittent operation of these coders when energy is applied to the back stationary contacts associated with these movable contacts 14 and 15. All of these double-throw contacts 10, 11, 12 and 13 normally assume their deenergized position in which they connect their respective line wires to relays, these contacts when in their raised or attracted position connecting their respective line wires to a source of current which is controllable by manually operable levers in the office and by automatically operated contacts at the field station to at times apply energy to the front points of these double-throw contacts. Instead of employing polar-neutral relays to detect presence and polarity of current transmitted through a line circuit a two-position mag-stick relay WKS and a neutral relay WK have been connected to the back point of the double-throw contact 10 at the office.

This mag-stick relay WKS is a polar relay which remains in the position to which it was last operated, which polar mag-stick relay WKS when assuming either its positive or its negative position connecting the relay WK in multiple with the winding of this relay WKS, so that the relay WK may manifest whether or not current is being received and if so whether this current is continuous or intermittent. This relay WK is provided with two windings preferably having their turns arranged oppositely and selected by a polar contact 54 of the relay WKS. From this it is apparent that pole changing of the current applied to the relay WKS will cause no pole changing of the magnetic flux in the core of the relay WK. Each of the other double-throw contacts 11, 12 and 13 when in their retracted position are connected to similar mag-stick relays and neutral relays. These mak-stick relays for the double-throw contacts 11, 12 and 13 have been designated WCS, TGKS and GCS, respectively, whereas their associated neutral relays have been designated WC, TGK and GC, respec-

tively. It may be pointed out that the relays WKS and WK are employed for receiving switch control indications at the office, whereas the relays TGKS and TGK are employed to receive both signal clear indications and track occupancy indications. Also, the relays WCS and WC are employed to control the switch control relay WZ, whereas the relays GCS and GC are employed to control the signal control relay GZ. 5 Since the neutral relays WK, TGK, WC and GC are quick acting relays and follow the impulses 10 that are transmitted over the line circuits, and 15 since continuous indications and controls are desired to be manifested slow dropping repeater relays have been provided for these relays WK, TGK, WC and GC and these slow dropping relays have been designated WKP, TGKP, WCP and GCP, respectively.

Under normal at-rest conditions, as illustrated, 20 all of the relays except the switch control relay WZ are deenergized as are also the indicators TE, OCE, GLE and GE. In order to simplify the 25 circuits symbols indicating (+), (—) or C have been applied to the starting point and the ending point of each circuit to designate the terminal (+), the terminal (—), or the common 30 return wire C to which these points of the circuits are connected. In order to complete these 35 circuits an office battery BO provided with a terminal (+) and a terminal (—) and having its mid-point connected to the common return wire C has been illustrated. At the field station a similar 40 source of current or battery BF has been illustrated which has been provided with a terminal (+), a terminal (—) and which has its 45 mid-point connected to the common return wire C. As already pointed out the switch control relay WZ (Fig. 1B) is normally energized, it being energized through a stick circuit including the polar contact 20, a stick contact 21 and the back contact 22 of the relay WCP. Although it has been stated that the track switch SW is at the end of a passing siding it should be understood that it may within the scope of the present 50 invention be located at a turn-out. In order to get a better understanding of the system, its mode of operation and the functions which it performs it is believed desirable to now consider the operation of the system.

Operation

Let us assume that there is an east-bound train on the main track of the passing siding PS, or other portion of the railroad approaching the track switch SW, and that it is desired to clear the signal 55 2 to allow this train to proceed over the track switch SW. Since the track switch already assumes its main track position it will be unnecessary to operate the switch control lever SML. 60 In order, however, to cause clearing of the signal 2 it will be necessary to operate the signal lever SGL to its east-bound, namely, its upper position. The operation of the lever SGL to its upper position causes closure of an energizing circuit for the coder 75CT which may be traced from the terminal (+), through the contact 25 of the lever SGL and through interrupter contact 14 and the winding of the coder 75CT. This will cause the coder 75CT to intermittently pick up 65 and drop its contacts 10 and 12 at the rate of substantially seventy-five times per minute. Intermittent closure of front contact 10 of coder 70 75CT causes intermittent picking up of relay WC and the continuous picking up of relay WCP. This results in closure of a different energizing

circuit, namely, a pick-up circuit, instead of the normal stick circuit for the relay WZ which produces no change in the position assumed by the relay WZ and the track switch SW.

Intermittent closure of the front contact 12 of this coder 75CT causes current of positive polarity to flow from the terminal (+), through the contact 26 of the signal lever SGL, through the back contact 27 of the out-of-correspondence relay OCR, through front contact 12 of the coder 75CT, through line wire GZ—GK—TK, through back contact 13 of the coder 120CT, and through windings of the relay GCS and GC in multiple to the common return wire C connected to the mid-point of the office battery BO. The intermittent closure of this circuit causes the mag-stick relay GCS to assume the proper polar position and causes intermittent picking up of the relay GC. Intermittent picking up of the neutral line relay GC causes intermittent closure of its front contact 29 and intermittent energization of the slow dropping line repeater relay GCP. This intermittent energization of line repeater relay GCP, since it is sufficiently slow dropping so as not to drop between the impulses of current received, causes its front contact 30 to be maintained closed continuously. Since the contact 31 of the mag-stick relay GCS assumes its right-hand position continuously the signal control relay GZ will have its positive polarity energizing circuit including these contacts 31 and 30 continuously closed, so that this signal control relay GZ is continuously energized to its right-hand energized position.

With the signal control relay GZ energized to the right an energizing circuit conventionally illustrated by the dotted line 35 and including suitable contacts controlled in accordance with traffic conditions in advance (illustrated by the letters X) is closed through the front contact 33 and the polar contact 34 of the signal control relay GZ. This control circuit 35 for the signal 2 of course also includes a contact 36 of the switch indication relay NWP, as conventionally illustrated. The closure of this circuit 35 will, of course, allow clearing of the signal 2 in accordance with traffic conditions in advance. Had the signal indication relay GZ been energized for setting up west-bound traffic, that is, energized to its left-hand position, a different signal clearing circuit 37, including a contact 39 of the switch repeater relay NWP, would have been closed.

The clearing of the signal 2, as for reasons just pointed out, causes deenergization of the signal-at-stop relay M, for reasons heretofore pointed out, as a result of which its back contact 40 closes an energizing circuit for the coder 120CT, causing intermittent operation of this coder at the 120 actuations per minute rate to cause the contact 13 to be lifted and dropped substantially 120 times per minute. Also, the dropping of the signal-at-stop relay M causes, by the closure of its back contact 41, current of positive polarity to intermittently flow from the terminal (+), through back contact 41 of relay M, through front contact 13 of coder 120CT, through back contact 12 of coder 75CT, through the winding of the mag-stick relay TGKS, to common return wire C, and also through a multiple branch including the polar contact 42 of the relay TGKS assuming its right-hand position and the lower winding of the neutral relay TGK from whence the current flows through the common return wire C, which is connected to the mid-point of the field battery BF.

The intermittent energization of the neutral relay TGK causes its front contact 44 to intermittently energize the slow dropping line repeater relay TGKP, and since this relay TGKP is sufficiently slow dropping so as not to drop between impulses this relay TGKP remains in its energized position continuously, during intermittent picking up of relay TGK, and closes its front contacts 45 and 46 continuously. The closed front contact 45 merely closes a multiple circuit for the indicating lamp GLE which was already closed at contact 43 when the signal lever SGL was moved to its upper east-bound position. The continuous closure of front contact 46 of this slow dropping line repeating relay TGKP however closes an energizing circuit for the signal indicator GE which circuit may be traced from the terminal (+), through front contact 46 of this relay TGKP, and through polar contact 47 of the mag-stick relay TGKS assuming its right-hand position. The operator is therefore informed by the illumination of indicating lamps GLE and GE, or by suitable other manifestation if some other form of indicator is employed, that an east-bound signal has been cleared on the actual track layout. This manifestation that an east-bound signal has been cleared is in part manifested by the position assumed by the signal control lever SGL. The picking up of the signal indicating relay TGKP not only causes illumination of the lamps GLE and GE to manifest that a proceed signal is being displayed or the illumination of the lamps GLE and TE to manifest that the detector track circuit is occupied but also performs an electric locking function by opening its back contacts 57 and 65. At open back contact 57 it prevents the switch lever SML, upon being moved to a new position maliciously or otherwise, from causing the relay OCR from picking up. For if relay OCR were picked up it would by opening its back contact 27 open the signal clearing circuit including relays GCS and GC in multiple. Also at open back contact 65 the relay TGKP prevents a new switch operating circuit being established at one point such circuit however being electrically locked open at open back contact 61 of relay GZ (see Fig. 1B) at the field station.

Let us now assume that the east-bound train approaching the signal 2 passes this signal 2 and in so doing treads upon the detector track circuit and causes deenergization of the track relay T. The dropping of the track relay T causes the signal 2 to assume its stop position, because this signal 2 is controlled in accordance with traffic conditions in advance, and this in turn causes the signal-at-stop relay M to again pick up to re-close its front contacts 38 and 41 and open its back contacts 40 and 41. The dropping of the detector track relay T also causes closure of its back contacts 50, 51 and 52 as a result of which the back contact 50 closes a new energizing circuit for the coder 120CT, so that this coder remains in continuous operation, the back contact 50 of track relay T closing before the back contact 40 of the signal-at-stop relay M opens. Also, closure of the back contact 52 of the track relay T results in the intermittent closure of an indication circuit traced from the terminal (—) of the field battery BF, back contact 52 of the track relay T, front contact 41 of the relay M, front contact 13 of the relay 120CT, front contact 12 of the coder 75CT, through the winding of the mag-stick relay TGKS, to the common return wire C, to the mid-point of the battery BF. This current of negative polarity causes the polar contacts 42 and

47 of the mag-stick relay TGKS to be operated to their left-hand position. The movement of the polar contact 42 to its left-hand position establishes a new branch circuit through the upper winding of the line relay TGK bridging around the winding of the mag-stick relay TGKS, so that this neutral line relay TGK is intermittently picked up in accordance with the impulses of current transmitted from the field station to the control office through the back contact 52 of the track relay T. This intermittent picking up of the line relay TGK will maintain the slow dropping line repeater relay TGKP in its energized position continuously as a result of which the track indicator TE is energized and rendered active through a circuit including the front contact 46 of the line repeater relay TGKP and polar contact 47 of the mag-stick relay TGKS assuming its left-hand position. The signal indicator GE is therefore rendered inactive, whereas the detector track indicating lamp TE is rendered active, thereby informing the operator that the signal 2 has been operated to its stop condition and that the detector track circuit at the field station has become and is still occupied.

As the train under consideration now moves beyond the track switch SW and allows the detector track relay T to again pick up the detector track indicator TE is rendered inactive and the signal 2 is again cleared as soon as the train gets beyond those track circuits (not shown), which enter into the control of the signal 2. Clearing of the signal 2 will of course cause the signal-at-stop relay M to again be deenergized resulting in the rendering of the signal indicator GE active.

Let us now assume that there is a west-bound train approaching the signals 1 and 1A and that the operator desires to have this train enter the side track of the passing siding PS or similar diverging route. The operator will, of course, first return his signal lever SGL to the middle position to cause the return of the signal 2 to its stop condition, resulting in the re-energization of the relay M and the extinguishment of the indicator lamp GE, it being understood that the track switch and switch machine cannot be operated so long as the relay M assumes its deenergized or retracted position. This prohibition against operation of the switch machine is by reason of locking circuits provided to prevent the switch machine SM being operated under unsafe conditions. These locking circuits, well known in the art, have not been specifically illustrated, but have been shown conventionally by the relay L. Movement of the signal lever SGL to its middle position will of course put the signal 2 to stop and causes the indicating lamps GLE and GE to be extinguished and will cause the contact 57 of relay TGKP included in the energizing circuit of relay OCR and the contact 65 included in the switch control circuit to reclose to allow the coder 15CT to be oscillated and the track switch to be operated in response to movement of the lever SML.

Let us now assume that the operator in his desire to have the approaching train enter the side track of the passing siding PS operates his switch lever SML to its upper, or take-siding position. Movement of the contact 55 of the switch lever SML to its upper position closes an energizing circuit for the out-of-correspondence relay OCR which may be traced from the terminal (+) of the office battery BO, through the contact 56 of the mag-stick relay WKS assuming its right-hand position, through contact 55 of the

switch control lever SML, through back contact 51 of the line repeater relay TGKP, through the winding of the out-of-correspondence relay OCR, to the common return wire C connected to the midpoint of the office battery BO. Closure of this circuit causes the out-of-correspondence relay OCR to assume its energized position resulting in the closure of its front contacts 58 and 59 and the opening of its back contact 21. The closure of its front contact 59 renders the out-of-correspondence indicator OCR active to inform the operator that an out-of-correspondence condition between his switch control lever SML and the track switch in the field now exists. The opening of the back contact 21 of this out-of-correspondence relay OCR opens the signal control circuit heretofore traced and including the signal control contact 26. The closure of the front contact 58, on the other hand, of this out-of-correspondence relay OCR establishes a different energizing circuit for the coder 15CT. The closure of this coder circuit of course causes the coder 15CT to intermittently pick up its contacts 10 and 12 at a substantially 75 impulse per minute rate.

With the double-throw contact 10 of the coder 15CT now intermittently assuming its raised position and the switch lever SML assuming its raised position a negative energizing circuit for the mag-stick relay WCS at the field station is intermittently closed. This circuit may be traced from the terminal (-) through the contact 60 of the switch control lever SML, back contact 65 of relay TGKP, front contact 10 of the coder 15CT, line wire WZ-WK, back contact 11 of the coder 120CT (now at rest), through the back contact 61 of the signal control relay GZ, through the winding of the mag-stick relay WCS, to the common return wire C connected to the mid-point of the office battery BO. Since the current flowing in this circuit is of negative polarity the mag-stick relay WCS will be operated to its left-hand position where it will remain in spite of intermittent deenergization of this line circuit. This causes its polar contact 62 and 63 to assume the left-hand position. Also, with the polar contact 62 assuming its left-hand position the lower winding of the neutral line relay WC is intermittently energized since it is connected in multiple with the winding of the mag-stick relay WCS as a result of which the front contact 64 of the neutral line relay WC is intermittently closed, resulting in the intermittent energization of the slow dropping line repeater relay WCP. This repeater relay WCP is sufficiently slow dropping so that it will not drop in spite of the intermittent interruption of the switch control circuit including the line wire WZ-WK just traced. The picking up of the line repeater relay WCP, by the opening of its back contact 22, interrupts the stick circuit for the switch control relay WZ thereby causing this relay to assume its deenergized retracted position.

With the polar contact 63 of the mag-stick relay WCS now assuming its left-hand position the switch control relay WZ is now energized by current of negative polarity which flows from the terminal (-) of the field battery BF, through contact 63 of relay WCS assuming its left-hand position, and through front contact 22 of the line repeater relay WCP. This current of negative polarity causes the switch control relay WZ to assume its left-hand energized position as a result of which the reverse circuit R instead of the normal circuit N for the switch machine SM

is closed. Operation of the switch control relay WZ to its reverse position breaks the energizing circuit, including contacts 18 and 19 of relay WP and including contacts 16 and 17 of this relay WZ, for the correspondence relay NWP. The circuit for the switch indicating correspondence relay RWP also including these contacts 16 and 17 is however not closed because the contact 24 is open and the contact 23 will open as soon as the switch machine has been unlocked for its reverse operation. This reverse circuit for the switch machine SM may be traced from the terminal (+) of the field battery BF, front contact 66 of lock relay L, front contact 67 of the relay WZ, polar contact 68 of this same relay assuming its left-hand position, the reverse wire R and apparatus of the switch machine SM, through the common return wire C connected to the mid-point of the field battery BF. The closure of this reverse circuit for the switch machine SM causes this switch machine to unlock as a result of which the switch repeater relay WP assumes its deenergized position causing opening of its front contact 18 in the energizing circuit for the correspondence switch indication relay NWP. The closure of the back contact 70 of the relay NWP establishes an energizing circuit for the coder 120CT, so that this coder 120CT causes intermittent picking up and dropping of its contacts 11 and 13. During the operation of the switch machine from its normal to its reverse position the polar contact 71 will remain in its right-hand or main track position until the switch machine SM has completed its stroke. During this time current of positive polarity may flow from the terminal (+) through the polar contact 71 of the switch repeater relay WP, through front contact 51 of the track relay T, through front contact 38 of the signal-at-stop relay M, through front contact 11 of the coder 120CT, through line wire WZ—WK, through back contact 10 of the coder 75CT, through the winding of the mag-stick relay WKS, to the common return wire C connected to the mid-point of the field battery BF. Since this current is of positive polarity the polar contacts 54 and 56 of the mag-stick relay WKS will continue to assume their right-hand position. This contact 54 of course establishes a circuit through the lower winding of the neutral line relay WK so that this relay WK intermittently closes its front contact 73 to cause the slow dropping line repeater relay WKP to continuously assume its attracted position so long as the line circuit just traced is intermittently closed.

It should be understood that the circuit through back contact 10 of coder 75CT and front contact 11 of coder 120CT is closed contemporaneously with the circuit for controlling switch machine SM and including front contact 10 of coder 75CT and back contact 11 of coder 120CT. With the line repeater relay WKP now assuming its energized position its front contacts 74 and 75 are closed thereby establishing a supplemental circuit for the out-of-correspondence lamp OCE which lamp was already energized through the front contact 59 of the relay OCR. This supplemental circuit extends through the front contact 75 of this relay WKP. The front contact 74 of this relay WKP establishes an auxiliary circuit for the out-of-correspondence relay OCR. The out-of-correspondence relay OCR is therefore maintained energized so long as an indication is received over the switch control and indication circuit WZ—WK.

As soon as the switch machine SM completes its

stroke the switch indication relay WP is operated to its left-hand position in which position its polar contact applies negative polarity instead of positive polarity to the mag-stick relay WKS. Operation of contact 56 of relay WKS to the left results in opening of the pick-up circuit for out-of-correspondence relay OCR. A short time after relay WP assumes its energized position its slow acting repeater correspondence relay RWP also assumes its energized position as a result of which its back contact 72 is opened, thereby preventing the operation of the coder 120CT, and thereby discontinuing the transmission of an indication from the field to the central office over the line circuit WZ—WK, that is, insofar as the condition of the track switch SW and its switch machine SM is concerned. Upon discontinuance of this transmission of an indication from the switch machine to the central office the relays WK and WKP will of course be both continuously deenergized, thereby causing the opening of contacts 74 and 75 of the line repeater relay WKP resulting in the deenergization of the out-of-correspondence relay OCR. Since the relays WKP and OCR are now both deenergized, and with their respective contacts 75 and 59 open, the out-of-correspondence lamp OCE is extinguished informing the operator not only that the polar contacts 71 of relay WP have been operated to the left but also that back contacts 70 or 72 of relays NWP and RWP, respectively, have been opened. This signifies to the operator that the switch machine SM and its associated track switch SW assume the same position as does the switch control lever SML in the control office.

The switch indication circuit heretofore traced and starting at the contact 71 of the switch indication relay WP also included the front contact 51 of the track relay T. In the event a train should get beyond the insulating joints 9 at one end of the detector track circuit before the switch machine SM has had an opportunity to complete its stroke and reenergize its repeater relay WP the switch indication circuit would include the back contact 77 of the switch repeater relay WP and the back contact 51 of the detector track relay T. It may be pointed out that the switch machine control circuits in the system disclosed are so organized, as well known in the art, as to permit completion of the stroke of the switch machine if such switch machine is initiated while the detector track relay is energized. That is, if the detector track circuit becomes occupied before the switch machine has had an opportunity to complete its stroke an auxiliary circuit will allow continued energization and operation of the switch machine until its stroke has been completed. Since the feature of completing the stroke of the switch machine under the conditions assumed above is well known in the art the specific circuits for performing this function have not been shown. In this connection it should be observed that the system of the present invention permits out-of-correspondence and track occupancy indications to be transmitted independently and simultaneously as conditions require. This is made possible because these indications are transmitted over different line circuits.

Since the operator desires to allow the west-bound train to proceed onto the side track, or a diverging track, as is now possible with the track switch SW assuming its reverse position, the operator will operate his signal lever SGL to its lower or west-bound position. With the contact 25 of the signal lever SGL assuming its lower

position an energizing circuit for the coder 75CT is closed through its interrupter contact 14 to cause intermittent energization of this coder 75CT, resulting in intermittent lifting and dropping of its contacts 10 and 12. With the contact 26 of the signal lever SGL assuming its lower position current of negative polarity may intermittently flow to the field station through a circuit starting at the (—) terminal of the office battery BO, contact 26 of the signal lever SGL assuming its lower position, back contact 27 of the out-of-correspondence relay OCR, front contact 12 of the coder 75CT, line wire GZ—GK—TK, back contact 13 of the coder 120CT, through the winding of the mag-stick relay GCS to the common return wire C connected to the mid-point of the office battery BO. The intermittent completion of this circuit by the intermittent closure of back contact 12 of coder 75CT causes intermittent current pulses of negative polarity to flow through the winding of the mag-stick relay GCS causing operation of its polar contact 28 to the left-hand position where they will remain continuously to establish a circuit for the neutral line relay GC including this contact 28 and bridged across the winding of the mag-stick relay GCS. The net result is that the neutral line relay GC intermittently closes its front contact 29 in response to the impulses transmitted and causes continuous closure of front contact 30 of the line repeater relay GCP which latter relay is controlled through this contact 29.

With the polar contacts of the relay GCS assuming the left-hand position and with the front contact 30 of the line repeater relay GCP closed a circuit for the signal control relay GZ for energizing this relay with current of negative polarity is closed to result in the operation of this signal control relay GZ to its left-hand energized position.

With the signal control relay GZ energized to its left-hand position and with the switch repeater relay WP energized to its left-hand position an energizing circuit conventionally illustrated by a dotted line 31 for the mechanism on the take-siding signal 1A is closed. The closure of this circuit causes the take-siding signal 1A to indicate proceed in response to which the approaching west-bound train may enter the side track or diverging route over which this signal 1A governs traffic. This circuit illustrated in part by dotted line 31 includes front contact 48 of the switch correspondence relay RWP but does not include a traffic controlled contact X because the side track of the passing siding is assumed not to be track circuited. Attention is directed to the fact that a back contact 61 of the signal control relay GZ is included in the control circuit for controlling the switch machine SM through the medium of the line wire WZ—WK. This provision is made to prevent a switch control being transmitted from the central office to the field station while the signal control relay GZ is energized. This serves as an additional check against the operation of the switch machine while a signal-at-stop control is transmitted to the field station which might result in the clearing of a signal. It is of course understood that in practice the switch machine SM could not be operated unless the signal-at-stop relay M were then in its attracted position. The contact 61 therefore may be effective before the relay M has had time to respond. Attention is also directed to the back contact 57 of the relay TGKP (Fig. 1A) included in the energizing circuit for the out-of-corre-

spondence relay OCR. This feature prevents an out-of-correspondence indication being given if the switch control lever SML is operated while an indication signifying a proceed signal indication in the field or a track occupancy indication is given. It also prevents operation of the coder 75CT in response to an out-of-correspondence condition of the switch machine control lever SML and the mag-stick indication relay WKS. It also prevents picking up of the relay OCR by movement of the switch control lever SML during a signal clearing condition, which is desirable, for otherwise a clear signal could be put to stop by operation of this switch control lever. In this connection attention is directed to the back contact 27 of relay OCR included in the signal clearing circuit.

Another electric interlocking feature consists in the provision of the back contact 65 of the relay TGKP included in the switch control circuit. This contact 65 prevents a switch control being transmitted to the field station while either a track occupancy or a signal-clear indication is being received. This is desirable for even though operation of the track switch SW is prevented by local interlocking and approach locking contacts, such as by the contact 66 of the lock relay L, under the assumed condition, it is desirable not to transmit a new switch control to the field station when either an OS indication or a signal-at-proceed indication is being received.

Graphs Fig. 2.—In the foregoing part of the specification it has been generally stated that the control circuits and the indication circuits over the line wires WZ—WK and GZ—GK—TK are closed and energized intermittently and at times contemporaneously. In order to more clearly point out what the nature of this intermittent closure of various circuits is, Fig. 2 has been added to illustrate how the various circuits including a single line circuit are controlled in beat-frequency fashion. Referring to Fig. 2 of the drawings the numbers starting at zero and ending at seven shown in the top line and designated SEC denote time from left to right in seconds. In other words, in moving from left to right over Fig. 2 of the drawings it must be assumed that time passes in seconds as signified by these numbers. The first graph designated 75CTG signifies the action of the contacts of coder 75CT as compared with the passing of time. Each of the top lobes or waves of this curve designate that front contacts 10 and 12 of coder 75CT are closed whereas the valleys in this curve designate that back contacts 10, 12 and 14 of this coder 75CT are closed. If each of these lobes and valleys is considered to be a cycle, as is the case, it will be seen that 7½ cycles elapse during the first six seconds of the lapse of time, or in other words, the coder 75CT operates at a 75 energizations and deenergizations per minute rate. Similarly, the second graph 120CTG signifies that this coder 120CT picks up and drops away 120 times a minute. This is evident from the fact that two complete cycles exist for each second of the lapse of time. Referring to Figs. 1A and 1B of the drawings it will be seen that the line circuit comprising line wire WZ—WK and common return wire C may be completed in four different ways of which the first circuit, namely "circuit 1" is a line circuit including front contact 10 of coder 75CT and back contact 11 of coder 120CT, of which the second circuit, namely "circuit 2" includes back contact 10 of coder 75CT and front contact 11 of coder 120CT,

of which the third circuit includes the relays at both the control office and the field station in series and passes through back contacts 10 of coder 75CT and back contact 11 of coder 120CT, and of which the fourth circuit includes the sources of current at both the central office and the field station in series and which includes front contact 10 of coder 75CT and front contact 11 of coder 120 CT. The intermittent connecting of the batteries in series is not considered harmful in view of the appreciable line resistances involved. The intermittent closure of these four different circuits have been illustrated graphically in Fig. 2 of the drawings by ways in graphs C¹ (circuit 1); C² (circuit 2); CR (relays in series) and CB (batteries in series).

By referring to these four graphs illustrated in Fig. 2 of the drawings it will be seen that one of these four circuits is closed at all times, and that at no time are two of these circuits closed simultaneously. In other words, these four circuits are so closed in sequence that one of the circuits is closed at all times and it will be seen from these graphs that each of the circuits is closed intermittently without appreciable gaps of open circuit condition between successive closures.

Nothing has been stated hereinbefore in regard to the putting of a signal to stop after a signal has been cleared, but it is readily understood that movement of the signal lever SGL to its intermediate position from an extreme position will result in the deenergization of the repeating neutral line relay GCP and the opening of its contact 30 which will result in deenergization of the signal control relay GZ and the placing of the particular signal which was then clear into its stop condition.

Having thus shown and described one rather specific embodiment of applicant's invention it should be understood that the specific structure illustrated has been selected to facilitate the description of applicant's invention and its mode of operation in order that the underlying principles of applicant's invention may be understood and should not be considered as a showing of all forms the invention may take nor in a limiting sense, and it is further desired to be understood that various changes, modifications, and additions to the specific structure illustrated may be made without departing from the spirit or scope of the invention so long as these changes come within the scope of the appended claims.

What I claim as new is:

1. In a centralized traffic controlling system of the unit line wire type for railroads, in combination with a line circuit connecting a central office and a distant field station, a control source of current and an indication relay at said office, an indication source of current and a control relay at said field station, control means for connecting said control source to an office branch wire or leaving it disconnected, indication means for connecting said indication source to a field branch wire or leaving it disconnected, normally at rest oscillatory contacts one at said office and one at said field station each for when active alternately connecting the associated source and branch wire and the associated relay into said line circuit but when at rest connecting the associated relay into said line circuit, electro-responsive means for operating said oscillatory contacts either separately or both at a time and when both are operated at a time operating them at different rates such that both a control circuit and an indication circuit are intermittently established each

at a sufficiently rapid rate and for periods of sufficient durations that a substantially continuous control consisting of a series of current impulses and a substantially continuous indication 5. consisting of a series of current impulses to effectively control said control relay and said indication relay respectively may be transmitted in opposite directions over said line circuit contemporaneously, and means for rendering the electro-responsive means at the controlled end active when an indication is to be transmitted from that end.

2. In a centralized traffic controlling system of the unit line wire type for railroads, in combination with a line circuit connecting a central office and a distant field station, a control source of current and an indication relay at said office, an indication source of current and a control relay at said field station, control means for connecting said control source to an office branch wire or leaving it disconnected, indication means for connecting said indication source to a field branch wire or leaving it disconnected, normally inactive oscillatory contacts one at said office and one at said field station for when active alternately connecting the associated source and branch wire and the associated relay into said line circuit and when inactive connecting only the associated relay into said line circuit, means for operating said oscillatory contacts at frequencies such that if both of said oscillator contacts are active the beat-frequency of the two oscillatory contact frequencies is high enough to avoid long periods of synchronism conditions so that two-way transmission over said line circuit is effective, and means for rendering the oscillatory contacts at that end of said line circuit from which a control or an indication is transmitted active and for automatically rendering it inactive when the apparatus to be controlled has responded.

3. In a centralized traffic controlling system for railroads of the unit line wire type comprising, a line circuit connecting a central office and a distant field station, a control source of current and an indication relay at said office, an indication source of current and a control relay at said field station, control means for connecting said control source of a particular polarity to an office branch wire or leaving it disconnected, indication means for connecting said indication source to a field branch wire or leaving it disconnected, oscillatory contacts one at said office and one at said field station each when operated alternately connecting the associated source and branch wire and the associated relay into said line circuit but normally inactive and when inactive connecting the associated relay into said line circuit, said oscillatory contacts being normally inactive and when both active operating at different rates such that both a control circuit and an indication circuit are intermittently established at sufficiently rapid rates which circuits are maintained for sufficient durations that a substantially continuous control channel and a substantially continuous indication channel over which to control said relays are established over said line circuit contemporaneously, and means for operating the oscillatory contacts at either or both ends and when operating them at one end only then operating them at that end from which a control or indication is transmitted and only when such control or indication is being transmitted.

4. In a centralized traffic controlling system for railroads of the unit line wire type comprising, a line circuit connecting a central office and a dis-

tant field station; a control source of current and an indication relay at said office, an indication source of current and a control relay at said field station, control means for connecting said control source to an office branch wire or leaving it disconnected, indication means for connecting a particular polarity terminal of said indication source to a field branch wire or leaving it disconnected, normally inactive oscillatory contacts one at said office and one at said field station each when active alternately connecting the associated source and branch wire and the associated relay into said line circuit, means for operating said oscillatory contacts at either or both ends and operating them at different rates such that when both are operated at the same time both a control circuit and an indication circuit are intermittently established at sufficiently rapid rates and for periods of time long enough such that if both of said oscillatory contacts are active a substantially continuous control channel and a substantially continuous indication channel are established in opposite directions over said line circuit contemporaneously, and means for rendering the means for operating the oscillatory contact at the office active when a control is to be transmitted and rendering the means for operating the oscillatory contact at the field station active when an indication is to be transmitted and for at times rendering both of said last mentioned means active contemporaneously.

5. In a centralized traffic controlling system for railroads of the unit line wire type comprising, a line circuit connecting a central office and a distant field station, a control source of current and a polar indication relay at said office, an indication source of current and a polar control relay at said field station, control means for connecting said control source of a particular polarity to an office branch wire or leaving it disconnected, indication means for connecting a particular polarity terminal of said indication source to a field branch wire or leaving it disconnected, normally inactive oscillatory contacts one at said office and one at said field station each when active alternately connecting the associated source and branch wire and the associated relay into said line circuit, said oscillatory contacts when both active operating at different rates such that both a control circuit and an indication circuit are intermittently established at sufficiently rapid rates and for periods of time long enough such that a substantially continuous control channel and a substantially continuous indication channel are established in opposite directions over said line circuit contemporaneously, electro-responsive means for each oscillatory contact to oscillate the same, and means for rendering the electro-responsive means at said central office active when said control means is operated for rendering the electro-responsive means at said field station active when said indication means is operated and for rendering both of said electro-responsive means active when the control means and indication means are both operated.

6. In a centralized traffic controlling system for railroads, the combination with a central office and a distant field station, a power operated track switch at said field station, a line circuit connecting said office and field station, a control lever for controlling said track switch through the medium of said line circuit, a correspondence relay at said office having an energizing circuit

10 closed if said lever and said track switch assume non-correspondence positions, an indication relay at said office and controlled over said line circuit and energized so long as an indication of the position assumed by the track switch is transmitted from said field station to said office, means for transmitting from said field station to said office the position assumed by said track switch while in transit and for a short time thereafter, and an auxiliary energizing circuit for said correspondence relay including a front contact of said indication relay.

15 7. In a system for transmitting controls in opposite directions over a single line circuit comprising, a line circuit connecting a first station and a second station, a first control means including a control source and a second electro-responsive means at said first station, a second control means including a control source and a 20 first electro-responsive means at said second station, normally inactive oscillatory contacts at each of said stations which when rendered active alternately connect the control source and the electro-responsive means at that station to the line circuit and when inactive connect only such electro-responsive means to such line circuit, means at said first station for at times rendering both said first control means and the oscillatory contacts at such first station active, means at 25 said second station for at times rendering both said second control means and the oscillatory contact at such second station active, said oscillatory contacts each when active alternately connecting the associated source and the associated 30 electro-responsive means into said line circuit and operate at different rates such that if both oscillatory contacts are simultaneously active control circuits in both directions over said line circuit are intermittently established each control means transmitting successive impulses of current at a sufficiently rapid rate with the impulses extending for sufficient durations of time that a substantially continuous control is transmitted in both directions over said line circuit contemporaneously, and means at one of said stations for 35 rendering the oscillatory contacts at such station active when a control or an indication is transmitted from that station and for rendering them automatically inactive when the apparatus to be controlled has responded.

40 8. In a centralized traffic controlling system of the unit line wire type for railroads, in combination with a line circuit connecting a central office and a distant field station, a control source of current and an indication relay at said office, an indication source of current and a control relay at said field station, control means for connecting said control source to an office branch wire or 45 leaving it disconnected, indication means for connecting said indication source to a field branch wire or leaving it disconnected, normally inactive oscillatory contacts one at said office and one at said field station for when active alternately connecting the associated source and branch wire and the associated relay into said line circuit, electro-responsive means for each oscillatory contact for operating said 50 oscillatory contacts at frequencies such that if both of said oscillator contacts are active the beat-frequency of the two oscillatory contact frequencies is high enough to avoid long periods of synchronism conditions so that two-way transmission over said line circuit is effective, and means for rendering the electro-responsive means

at that end of said line circuit from which a control or an indication is transmitted active and rendering both of said electro-responsive means active when both a control and an indication is to be transmitted contemporaneously.

9. In a centralized traffic controlling system for railroads, the combination with a central office, a line circuit extending from said central office, a switch control lever and switch indication means at said office, a double-throw contact connected to the office end of said line circuit, electro-magnetic means for alternately and intermittently connecting said line circuit to said switch control lever and said switch indication means, a relay for when in an energized condition rendering said electro-magnetic means active, a first circuit for said relay closed only when said switch control lever and said switch indication means assume non-correspondence positions, and a second circuit for said relay closed when said switch indication means is in its active condition.

10. In a centralized traffic controlling system for railroads, the combination with a central office, a line circuit extending from said central office, a switch control lever and switch indication means at said office, a double-throw contact connected to the office end of said line circuit, electro-magnetic means for alternately and intermittently connecting said line circuit to said switch control lever and said switch indication means, and means for rendering said electro-magnetic means active effective when said switch control lever and said switch indication means assume non-correspondence positions and also

effective while a switch position indication is being received over said line circuit irrespective of whether or not the received indication is in agreement with the position then assumed by said switch control lever.

11. In a centralized traffic controlling system, the combination with a central office and a field station, of two line wires connecting said office and field station, a control source and a plurality of indication relays at said office, an indication source and a plurality of control relays at said field station, control means for connecting said control source to one, the other, or both of two office branch wires, indication means for connecting said indication source to one, the other, or both of two field branch wires, normally inactive oscillatory contacts two at the office end and two at the field station end of said line wires for when active alternately connecting the associated branch wire and the associated relay to each of said line wire ends and when inactive connecting only the associated relay to its line wire end, a single electro-magnetic means for each of said two oscillatory contacts for oscillating the same, means for rendering the office electro-magnetic means active when a control is to be transmitted and for rendering the field station electro-magnetic means active when an indication is to be transmitted and rendering both of said electro-magnetic means active when controls and indications are to be transmitted contemporaneously.

THOMAS J. JUDGE.
